UNITED STATES PATENT OFFICE.

THOMAS J. KERWIN, OF CHICAGO, ILLINOIS.

INSTRUMENT-BOARD LAMP.

Application filed August 20, 1921. Serial No. 493,872

To all whom it may concern:

Be it known that I, THOMAS J. KERWIN, citizen of the United States, residing at Chicago, in the county of Cook and State 5 of Illinois, have invented certain new and useful Improvements in an Instrument-Board Lamp; and I do hereby declare the following to be a full, clear, and exact description of the invention, such as will enable others skilled in the art to which it 10 pertains to make and use the same.

My invention relates to means for controlling the direction in which light is emitted from a lamp, its general objects including those of providing simple and effective means whereby the light from a given lamp can normally be confined to beams issuing in predetermined directions and whereby light may also be afforded in 20 additional directions when desired.

More particularly, my invention relates to lamps adapted for use on instrument boards and the like, where a number of different appliances require illumination, and aims to 25 shield the direct rays of light from the eyes of the observer while adequately illuminating the appliances in connection with which the lamp is used. For example, in automobile practice it is customary to mount an 30 oil indicator as well as a battery ammeter and a speedometer on the dashboard of the vehicle and it is important that the indicating portions of such instruments should be adequately illuminated at night. It is also 35 important that none of the rays of light from the lamp should issue directly toward the occupants of the automobile so as to cause a blinding glare, and the issuing light should preferably be confined to the dials of 40 the instrument so as not to create a glare effect on a reduced scale when the driver of the vehicle is looking elsewhere than on the instrument, as every such glare-producing effect will reduce the readiness with which 45 the driver can observe what is ahead of his vehicle. Dashboard lamps or switch-board lamps as heretofore constructed for this purpose have commonly been provided with 50 cowls hooding the lamps and each equipped 55 with an opening on one side of ample size for permitting light to be emitted towards adjacent instruments while shielding the eyes of the driver from the direct rays of the lamp. In so doing, a considerable portion of the emitted light has been wasted on 60 portions of the dashboard or switchboard

which do not ordinarily require illumination and likewise wasted by being directed towards the floor of the car, thereby creating a general brightness in front of the driver 60 of the vehicle which interferes somewhat with his visual acuity. Moreover, the cowls as commonly used for this purpose have wasted a considerable proportion of the light 65 of the lamp by reflecting the same from inner surfaces of the cowl into the interior of the latter, which is undesirable.

My invention aims to overcome these various objections to the arrangements heretofore in use by providing a more efficient 70 cowl or hood arrangement adapted to concentrate the emitted light normally along beams issuing in predetermined directions, and also aims to provide simple means whereby the extent and direction of the 75 emitted light may be increased at the will of the operator so that the lamp may also illuminate the floor in front of his seat. Furthermore, my invention aims to provide 80 an inexpensive construction adapted for such purposes and one which can readily be employed in connection with standard types of dashboard or switch board lamps. Still further and more detailed objects will appear from the following specification and 85 from the accompanying drawings, in which

Fig. 1 is a fragmentary elevation of the dashboard of an automobile, showing a cowl lamp embodying my invention as employed in connection with three instruments mounted 90 on the dashboard.

Fig. 2 is an elevation of the complete lamp socket employed in Fig. 1.

Fig. 3 is a central and longitudinal section through the same, taken along the correspondingly numbered line in Fig. 2.

Fig. 4 is a horizontal section taken through Fig. 2 along the correspondingly numbered line of that figure.

Fig. 5 is an enlarged and fragmentary 100 vertical section taken along the correspondingly numbered line of Fig. 2 and showing the means employed for normally latching the sliding collar in position.

Fig. 6 is a vertical section taken through 105 the dashboard of the automobile longitudinally of the latter, or along the line 6-6 of Fig. 1 but on a reduced scale, and showing how the lamp of my invention illuminates the floor of the car adjacent to the 110 dashboard when the sliding collar is moved out of its normal position.

In the drawings, I am showing the dashboard 1 as carrying a lamp socket which has a threaded shank 2 extending through the dashboard and clamped to the latter by a nut 3 in the usual manner, and which has its forward casing portion 4 equipped with bayonet slots 5 for engaging the usual lateral projections on the base 6 of a lamp 7. Adjacent to its base, the socket also has 10 its shell enlarged to afford a cylindrical portion 8 slidably fitting an apertured cylinder 9 which forms a part of the cowl and which is latched to the said cylinder by the interlocking of corresponding indentations 15 as shown at 10 in Fig. 3. The cylindrical casing portion 9 of the cowl is equipped with apertures 11, 12 and 13, all of which desirably have their axes substantially in the same plane transversely of the socket as that in which 20 the filament of the lamp is disposed, it being understood that lamps used for this purpose are standardized as to their dimensions. The forward end of the casing portion 9 is closed by an end portion 14, 25 which may be arched as shown in the drawings to improve the ornamental appearance and which is desirably made integral with the lateral casing portion 9. The interior of the casing portion 9 is desirably of highly 30 polished material so that it will readily reflect light striking against the same and will direct some of this light out through the said apertures, and the effective forward end of the casing is likewise desirably made of 35 a highly polished reflecting material. This endward reflecting surface might be the interior of the dome 14, but for increased efficiency I preferably mount within the forward end of the casing portion 9 an auxiliary reflector 40 15 having a lateral flange 16 tightly fitting the bore of the said casing and having its main portion 17 in the form of a cone directing its tip towards the lamp. Thus arranged, it will be obvious from the dotted 45 lines in Fig. 3 that this reflector will redirect rays of light from the lamp out through the said apertures while the corresponding rays would be largely wasted if allowed to pass freely into the dome 14. 50 By suitably spacing the apertures 11, 12, and 13, circumferentially of the cowl I can readily cause the emitted light to issue along beams directed towards the adjacent instruments, such as the oil gage 18, the ammeter 19, and the speedometer 20. However, as instruments are commonly set into the dashboard with their faces substantially flush with the face of the latter, the rays of light will be most effective if directed 55 obliquely against these instrument faces. I therefore desirably indent the casing 9 adjacent to and rearwardly of each of the apertures as shown in the drawings, so as to increase the extent to which light may issue 60 through each of these apertures toward the

dashboard. That is to say, I form the casing of the cowl so that the rearward edge of each light-emitting aperture will be curved inwardly of the casing. Consequently, the indentations 20, 21 and 22 which are respectively adjacent to the apertures 11, 12 and 13, will be substantially in the form of scoops gradually sloping outward rearwardly of the socket, as shown in longitudinal section in Fig. 3. 75

Thus arranged, it will be obvious that by suitably locating the apertures with respect to the relative location of the lamp and of the instruments which are to be illuminated, I can effectively light the faces of the latter without wasting light on any other objects, and that the confining of the rays of light to such oblique beams will leave the lamp effectively screened from the eyes of the occupants of the automobile. However, the light issuing through the forward halves of the said apertures would pass beyond the dashboard or towards the floor of the lamp where it ordinarily would be undesirable. To avoid this, I normally close 90 these forward portions of the apertures by a collar 23 which ordinarily is in the position shown in Fig. 3. This collar desirably is of such a size as to be freely slideable on the casing 9; so that it can be slid out of the way as shown in Figs. 2 and 6, thereby permitting the floor in front of the driver's seat and any objects adjacent to that floor to be lighted when desired. In practice, the casing portions between adjacent apertures may be rather narrow and can easily have slight humps 24 formed upon the same to underhang the collar 23 so as to yieldingly hold the latter in its normal position. 95 100 105

With a cowl lamp thus constructed, it will be evident that by moving the collar 23 from one position to the other I can readily secure either the illumination of the instruments alone as shown in Fig. 1 and as indicated by dotted lines in Fig. 3, or the lighting of the floor of the car also when the driver wishes to enter the latter or wants to observe any items on or adjacent to the floor. It will also be evident that the construction employed for this purpose is exceedingly simple and inexpensive to manufacture, particularly as the indenting of the casing adjacent to the perforations permits me to increase the emission of light towards the 110 board while employing a cylindrically sectioned die for punching each perforation. However, while I have illustrated and described my lamp-socket cowl in an embodiment including three apertures and one in 115 120 125 which the sliding collar is latched in position by humps on the casing between adjacent apertures, I do not wish to be limited to these or other details of the construction and arrangement thus disclosed, it being obvious 130

that the same might be modified in many ways without departing from the spirit of my invention or from the appended claims.

I claim as my invention:

5. 1. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, and a collar slidable on the hood and normally closing the portion of the apertures forward of the source of light, the socket having a portion between adjacent apertures formed for yieldingly latching the collar in its normal position. 40
10. 2. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, and means normally closing the forward portion of the said apertures. 45
15. 3. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, and a collar slidable on the hood and normally closing the portion of the apertures forward of the source of light. 50
20. 4. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, and a collar slidable on the hood and normally closing the portion of the apertures forward of the source of light. 55
25. 5. A lamp socket equipped for holding a lamp with its source of light in predetermined position, and a cowl hooding the lamp and having a plurality of light-emitting apertures spaced from each other circumferentially of the cowl, the side of the cowl being formed for increasing the emission of light rearwardly oblique of the socket, and movable means normally preventing the emission of light through the apertures in directions obliquely forward from the source of light. 60
30. 6. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, and a collar slidable on the hood and normally closing the portion of the apertures forward of the source of light, the hood having a rigid formation limiting the forward sliding of the collar and yielding formation normally preventing a rearward sliding of the collar. 65
35. 7. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, means normally covering the forward portion of the apertures, and a reflector mounted within the hood and disposed for reflecting light from the lamp rearwardly oblique of the axis of the socket through the uncovered parts of the apertures. 70
40. 8. A lamp socket equipped for holding an incandescent lamp, and a hood carried by the socket and inclosing the lamp and having on one side a plurality of light-emitting apertures all disposed in substantially alinement circumferentially of the hood and laterally opposite the source of light of the lamp, and a collar slidable on the hood and normally closing the portion of the apertures forward of the source of light, the socket having a portion between adjacent apertures formed for yieldingly latching the collar in its normal position. 75

Signed at Chicago, Illinois, August 15th, 1921.
